CLAIM

I claim the ornamental design for a vehicle side mirror, as shown and described.

DESCRIPTION

FIG. 1 is a right front perspective view of a vehicle side mirror showing the claimed design;

FIG. 2 is a right rear front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines enclosing low contrast or “ghost” areas of the drawing depict portions of the vehicle side mirror that form no part of the claimed design.
